SMOKING PIPE REAMER

Albert E. Collis, Salisbury, Mass.

Application September 17, 1938; Serial No. 230,419

4 Claims. (Cl. 131—246)

This invention relates to an improved smoking pipe reamer, and has for an object to provide a construction capable of ready adjustment for accommodating different size bowls of smoking pipes now on the market.

Another object of the invention is to provide a reamer for smoking pipes wherein a plurality of swinging jaws are provided with means for swinging the jaws to different adjusted positions to take care of pipe bowls of different sizes.

Another object, more specifically, is to provide a reamer for smoking pipes wherein a plurality of swinging jaws are presented with a sliding carrier for the jaws and means for rotating the jaws and carrier regardless of their positions, the structure being such that as the jaws are slid back and forth the outer ends of the jaws are swung inwardly or outwardly to accommodate different size bowls.

20 In the accompanying drawing—

Fig. 1 is a side elevation of a reamer ready for use with a smoking pipe shown in dotted lines in connection therewith;

Fig. 2 is a side view of the reamer shown in Fig. 1 but in a folded position ready to be stored away;

Fig. 3 is a vertical central view through the reamer shown in Fig. 1 with the jaws adjusted to a different position;

30 Fig. 4 is a transverse sectional view through Fig. 3 approximately on the line 4—4, the view being on an enlarged scale;

Fig. 5 is a transverse sectional view through Fig. 3, approximately on the line 5—5, the view being on an enlarged scale;

Fig. 6 is a side view of the ball and part of the stem shown in Fig. 3;

Fig. 7 is a view similar to Fig. 4 showing a modified form of the invention wherein a round stem or plunger is used;

Fig. 8 is a side view of a modified form of knob or thumb member for rotating the stem of the reamer.

Referring to the accompanying drawing by numeral, 1 indicates a pipe of any desired kind, as for instance the ordinary pipe now on the market provided with a bowl 2. A cake usually forms in the well 3 of the bowl and various means have heretofore been provided for removing this cake. In the present instance a reamer 4 is presented which functions to remove the cake readily substantially at all points in the well 3. The reamer 4 is provided with a flange or stem 5 having a thumb member or knob 6 preferably screwed on to the stem 5, as shown in Fig. 3.

The stem or flange 5 is polygonal in shape and as illustrated in the drawing is triangular so that the carrier 7 may slide thereon and yet be compelled to rotate therewith. The carrier 7 is provided with three arms 8 and each arm is provided with a jaw 9. The respective jaws are pivotally connected at their upper ends with the respective arms 8 by suitable pintle pins 10. Three jaws and associated parts have been provided but it will be evident that more or even less could be used without departing from the spirit of the invention. These jaws coat with a ball 11 having a number of grooves or notches 12, there being one notch 12 for each jaw 9. Preferably the ball 11 is screwed on to a threaded extension of the stem 5 so that it may be removed if desired. The bottoms of the respective grooves 12 are radially nearer the center of the axis of the stem 5 than the center of the respective pintle pins 10 so that when the parts are positioned as shown in Fig. 1 the lower ends of the jaws are almost in contact, but when the carrier 7 has been slid upwardly as shown in Fig. 3 the lower ends of the jaws move away from each other radially. This is to accommodate slightly different size bowls with the same reamer. It will be evident that the reamer may be made in two, three or more sizes as the market may demand.

Ordinarily the parts are arranged as shown in Fig. 1 and inserted into the bowl. After this has been done the thumb member or knob 6 is rotated once or as many times as desired. This rotation may be in one direction or in a back-and-forth direction. After a certain amount of reaming the pipe is removed and shaken out, after which a second reaming action may be performed if desired. Usually the carrier 7 is slid upwardly or toward the knob 6 a short distance so that the jaws will be somewhat spread and a better action secured. The jaws may have their outer edges formed at right angles to their sides so as to provide corners 13 and 14, or if preferred the outer edges may be sharpened.

When it is desired to place the reamer in the pocket or other storage place, the reamer is removed from the bowl of the pipe and the jaws swung over to the position shown in Fig. 2 whereby they will be nested beneath or opposite the knob 6. Preferably the rivets 10 hold the jaws sufficiently tight so that they will normally remain in any adjusted position except when forced therefrom by some little pressure. By reason of this function, the jaws will normally re-

main as shown in Fig. 2 but may be easily swung over to the position shown in Fig. 1.

Instead of having a triangular shaped stem 5, a round stem 5' could be used, as shown in Fig. 5 7, and a keyway 15 provided into which the end of a set screw 16 projects. This set screw in the present instance acts as a key and the groove or keyway 15 acts as a guide whereby the carrier 1 may freely slide but must rotate with the stem 10 or plunger 5'. Also the knob 6 could be formed with a flat end 6', as shown in Fig. 8, and merging into a hollow extension 17 having a slot 18 whereby it could fit over the end of the stem and over a suitable gear or lug so that by properly 15 rotating the member 6 the stem will be rotated. It will therefore be seen that the knob 6 may be found and knurled, as shown in Fig. 1, or may be flat and held in place in any desired manner either permanently or removably.

20 I claim:

1. A smoking pipe reamer comprising a stem triangular in cross section, a turning member at one end of said stem, a ball at the other end of said stem, a sliding member mounted to slide back and forth along said stem, said sliding member having a triangular-shaped aperture for accommodating said stem whereby said sliding member may freely slide back and forth on said stem and rotate therewith, and a plurality of 25 spaced reaming jaws pivotally mounted at one end on said sliding member, said ball having a notch for each of said jaws for guiding the jaws as they are moved by said sliding member, the pivotal mounting of said jaws being radially farther from the center of said stem than the bottom of the notches in said ball whereby as said sliding members moves away from said ball the outer ends of said jaws will swing radially away from each other.

2. A smoking pipe reamer comprising a stem, a spreading member at one end provided with spaced notches, a member mounted to slide on said stem but to turn therewith, a reamer jaw for each of said notches, and means for pivotally mounting one end of each of said jaws to said member radially farther from the center of said stem than the bottom of said notches whereby said jaws will swing inwardly and outwardly as said member slides back and forth on said stem. 10

3. A smoking pipe reamer comprising a stem polygonal in cross section, a carrier slidably mounted on said stem and rotatable therewith, said carrier having a plurality of radially extending arms, a jaw for each of said arms, means 15 for pivotally connecting one end of the respective jaws to the respective arms, means at one end of said stem for guiding said jaws and causing the same to spread when moved in one direction and permitting the same to swing so that 20 the outer ends will be substantially in contact when moved in the opposite direction, and a thumb-actuated member carried by said stem for rotating the stem, the carrier and the jaws.

4. A smoking pipe reamer comprising a stem 25 triangular shaped in cross section, a thumb member arranged at one end of said stem for rotating the same, a notched ball arranged at the other end of said stem, a carrier slidably mounted on said stem and rotatable therewith, and a jaw 30 pivotally connected to said carrier for each of said notches in said ball, said jaws being arranged to fit into said notches, the bottom of the notches being closer to the axis of said stem than the pivotal mounting of the jaws whereby 35 the free ends of the jaws will be swung outwardly as the carrier is slid toward said thumb member.

ALBERT E. COLLIS.
